UNITED STATES PATENT OFFICE.

ROBERT S. KINNEAR, OF LARAMIE, WYOMING, ASSIGNOR OF ONE-HALF TO ARTHUR P. HIGGINS, OF LARAMIE, WYOMING.

AUTOMATIC CAR-JOURNAL COOLER.

1,134,620.

Specification of Letters Patent.

Patented Apr. 6, 1915.

Application filed March 19, 1914. Serial No. 825,777.

To all whom it may concern:

Be it known that I, ROBERT S. KINNEAR, a citizen of the United States, residing at Laramie, in the county of Albany and State of Wyoming, have invented certain new and useful Improvements in Automatic Car-Journal Coolers, of which the following is a specification.

This invention relates to improvements in car-axle or journal boxes.

The invention has for its object, more particularly, to guard against the over-heating of the journal or axle, and the consequent "hot-box."

15 A further object is to provide for carrying out the aforesaid end automatically and in an effective manner and with facility.

The invention therefore consists of means for delivering a cooling agent to the axle or 20 journal and of subsidiary instrumentality substantially as hereinafter more fully disclosed and defined by appended claims.

In the accompanying drawings is illustrated the preferred embodiment of my invention, wherein it will be understood that various changes and modifications as to the 25 detailed construction and arrangement of parts may be made without departing from the spirit of the invention, and in which drawings—

Figure 1 is a side elevation of my invention. Fig. 2 is a view partly in longitudinal section and partly in elevation of the same. Fig. 3 is a partial longitudinal section thereof, parts being broken away. Fig. 4 is a transverse section of the device, the line of section being intermediate the manually actuated valve in the water or cooling agent pipe and the branches of said pipe. Fig. 5 40 is a fragmental sectional view of the same.

In carrying out my invention, I provide in connection with a journal axle box 1, having a suitable housing or casing 2 secured to the outer end thereof, a water-containing 45 receptacle 3 having a plug equipped opening 4 through which it may be supplied with water. Said receptacle 3 has suitably secured thereto and fitted therein, a compartment-chamber 5 with a wire screen member 6 facing the interior of the receptacle into the closed end or wall of which receptacle about centrally thereof, is secured or screwed a nozzle or short tubular member 7. The latter has its receiving end beveled the 55 same flaring outwardly and forming a valve-

seat 7^a which has fitted therein a correspondingly beveled valve 8 adapted to be held in unseated or open position by a resilient member or spring 9 effecting connection there-between and the screen 6. The valve 8 has its stem 8^a guided by means of spider-like members 10 attached thereto and movable within the tubular member or nozzle 7. A still further receptacle or chamber 11 has screw-threaded connection with the water-containing receptacle 3 and may abut the inner end-wall of the chamber 5, or be separated or spaced therefrom in which latter position, the valve 8 may be received and seated within the nozzle 7 under the action of the spring 9, thus providing for cutting off the flow of water to the journal or axle, as in effecting the cooling of the latter, as will presently more fully be understood.

A water-delivery pipe 12 is secured to or 75 threaded into the outer end wall of the chamber or receptacle 11 to the nozzle-provided end-wall of the compartment-chamber 5, said pipe 12 being in alignment with and receiving water from the nozzle 7, its intake 80 end also serving as a stop for the inner spider-like guide 10 of the stem 8^a of the valve 8, as seen particularly in Fig. 5, when the chambers 5 and 11 are in abutment, thus providing for the holding of the valve open 85 or unseated for the purpose aforesaid. The receptacle or chamber 11 has threaded or otherwise connected thereto, at one end a preferably outwardly flared or enlarged chamber 13 to and within the end of which member 13 is screw-threaded or otherwise connected a friction-plate 14, the same having frictional contact with a friction-plate terminal 15 of the axle or journal 16 suitably borne in the usual way in the box 1, which 90 friction plates will be further referred to later.

The water-pipe 12 is provided with a valve 17 having a hand disk or wheel equipped stem 18 for its convenient manual manipulation in providing for controlling the passage or delivery of the water therethrough. The pipe 12 is provided beyond the valve 17, with a "union" 19 by means of which connection is effected therebetween 100 and water-spraying or discharge pipes 20, the outer ends of said pipes being disposed so as to effect the discharge or spraying of the water upon the axle or journal, as seen particularly in Figs. 2 and 3, thus providing 105 110

for cooling or reducing the temperature of said journal or axle, and accordingly guarding against a "hot box."

- A plurality of additional pipes 21 suitably held in place in the inner end-wall of the chamber 12 and in the outer end wall of said chamber, so as to extend parallel with, and close to the water-pipe 12, a certain portion of their lengths are suitably curved
- 5 or carried upwardly, as shown in Fig. 3, their upper ends being disposed contiguous to the friction plate 14, and in the upper portion of the chamber 13 to receive the rising hot-air therein, resulting from the
- 10 heating action generated by the frictional contact between the journal carried plate 15 and the plate 14 as is obvious will take place. The hot air entering and passing into the pipes 21, it is apparent, will heat
- 15 said pipes and the radiated heat therefrom will cause the heating of the water pipe 12 and accordingly guard against the freezing of the water therein during the prevalence of low temperatures.
- 20 The structure resulting from the connected chambers 3, 11, and 13 is resiliently supported in position to conform to the incidental vibrations of the axle or journal within the housing or casing 2 by means of out-
- 25 standing studs 22 shown as castings with the chamber 11 and similar studs 23 shown as castings with the casing or housing, said studs receiving rods 24, suitably held therein, and encompassed by resilient members
- 30 or springs 25 held between said studs, as clearly disclosed by Figs. 3 and 2.

I claim—

1. A device of the type described including an attachment for a car-axle box
- 40 equipped with a cooling agent containing means, comprising chambers, one having a reticulated wall, the other chamber having a nozzle provided with a spring-controlled valve, with its controlling spring connected to said reticulated wall, the third chamber adapted to be spaced from the intermediate chamber for seating said valve, and a pipe alining said nozzle and provided with branch pipes or tubes adapted to deliver or
- 45 spray the cooling agent upon the car-axle.
- 50 2. A device of the type described includ-

ing an attachment for a car-axle box, and a cooling agent containing means comprising chambers, one chamber being provided with a nozzle having a spring-controlled valve, the third chamber being adjustable with respect to the second or intermediate chamber and adapted to retain said valve unseated when in contact with said intermediate chamber, a delivery pipe arranged to receive the cooling agent from said nozzle, and a plurality of pipes arranged parallel with and contiguous to said delivery pipe, and means adapted by frictional heat-generating action to deliver hot-air into said plurality of pipes during the prevalence of low temperature.

3. A device of the type described including an attachment for a car-axle or journal box, a cooling agent containing means, a sub-chamber within the cooling agent containing means proper having a reticulated wall in its otherwise open end through which the cooling agent enters said sub-chamber, the opposite wall of said sub-chamber having a valve-controlled nozzle extending therethrough, a third chamber having its casing adjustably connected to the casing of said sub-chamber, a fourth chamber having its casing connected to the casing of the third chamber and provided with a friction end-wall plate, the car-axle having a friction plate rotating in frictional contact with the aforesaid plate, a delivery pipe receiving the cooling agent from said nozzle, said delivery pipe having a plurality of branches adapted to spray or discharge the cooling agent upon the car-axle, and an additional plurality of pipes extending parallel and contiguous to said delivery pipe for a portion of their lengths, the remaining portions of said pipes extending upwardly into the upper portion of said fourth chamber and receiving the hot-air therefrom for heating by radiation, said delivery pipe during the prevalence of low temperature.

In testimony whereof I affix my signature in presence of two witnesses.

ROBERT S. KINNEAR.
